UNITED STATES PATENT OFFICE

HUGO ACKERMANN, OF GODESBERG-ON-THE-RHINE, GERMANY

PRESS

Application filed March 7, 1927, Serial No. 173,301, and in Germany February 20, 1926.

The invention relates to an improved separable press-table for brick presses, consisting of a frame, enclosing a rectangular opening, in which shorter and longer mould compartments for bricks of different sizes may be provided, without exchanging or disconnecting the frame elements of the press-table.

In the accompanying drawings:

Fig. 1 is a top view of the press-table showing the features of this invention.

Fig. 2 is a section through the press-table along the line N O in Fig. 1 showing two adjacent mould openings arranged abreast of on another.

Fig. 3 is a section through the press-table along the line P Q in Fig. 1.

Fig. 4 is a section along the line R S in Fig. 1, demonstrating the detachable connection of the frame elements of the press-table.

As a brick press, in which the new press-table may be used, a double pressure hydraulic press is assumed, having upper and lower press-cylinders, not shown in the drawings, connected and held in position by four pillars 31, which also support between the two press-cylinders a pair of fixed parallel frame elements 29. The distance apart of the fixed frame elements 29 is secured by a pair of detachable frame elements 30 connected to the frame elements 29 by bolts 32. The two pairs of frame elements forming the frame of the press-table enclose a rectangular opening in which the elements of the moulding box adapted to form the mould compartments 35 are adjustably arranged.

The inner sides of the frame elements 29, rigidly connected with the pillars 31, are each provided with a groove in which the two side cheeks 1 and 2 of the moulding box are displaceably mounted, being guided and held therein by means of suitably shaped lateral projections 33. The adjustable side cheeks 1 and 2 are supported against outward thrust by set screws 34 and 35 which are mounted

in the detachable frame elements 30 of the press-table.

The inner sides of the side cheeks 1 and 2 are provided with grooves, which support the transverse walls 3 of the mould compartments by means of suitably shaped projections 4 at both ends of the transverse walls 3. The transverse walls 3 are protected against wear by linings 15 also supported in the grooves of the side cheeks 1 and 2 by suitable projections 5 the length of which is greater than the depth of the grooves. These longer projections 5 of the linings 15 support the linings 16, protecting the side cheeks 1 and 2 against wear, and provided with lateral slots by means of which they are held on the projections of the linings 15.

The parts of the grooves in the side cheeks 1 and 2 behind the linings 16 and between the projections of the linings 15 are filled up by filling blocks 18, the length of which determines the width of the mould compartment whereas its length is determined by the length of the transverse walls 3.

Set screws 36, arranged in the fixed frame elements 29 bear against the outer transverse walls 3 which serve as end blocks.

In the example shown in the drawings two mould compartments for large bricks are provided by using three transverse walls 3. It is obvious, that other numbers of mould compartments of different width may be arranged between the fixed frame elements 29 provided, that the distance apart of the outer surfaces of the end blocks comes within the distance apart of the fixed frame elements 29. Also longer and shorter transverse walls 3 and linings 15 may be introduced between the adjustable side cheeks 1 and 2 for moulding longer or shorter bricks.

After introducing the transverse walls, linings and filling blocks adapted for the desired size and number of mould compartments between the adjustable side cheeks 1 and 2, the latter are brought and held in position

by suitably turning on the set screws 34 and 35. The right position of the mould compartments between the side cheeks 1 and 2 is adjusted and secured by suitably turning on the set screws 36. As the side cheeks 1 and 2 guided in the grooves of the fixed frame elements may be shifted in one direction and the transverse walls, linings and filling blocks may be removed gliding in the grooves of the side cheeks vertically to the shifting of the side cheeks, it is easy to adjust the mould compartments truly to the position of the corresponding upper dies 37 and lower dies 38, fixed respectively to the upper and lower press piston.

If other sizes or numbers of mould compartments are to be provided it is only necessary to loosen the set-screws 34, 35 and 36, to withdraw the side cheeks 1 and 2 outwardly till the projections of the transverse walls 3 and the linings 15 come out of the grooves in the side cheeks 1 and 2, and to exchange the transverse walls, linings and filling blocks against those suited for the desired shape and number of the mould compartments. After these parts are brought in position and after turning on the set screws 34, 35 and 36 the press-table is again ready for pressing. Thus for varying the size and number of the mould compartments no removing of the detachable frame elements 30 is required. The detachable connection between the frame elements 29 and 30 facilitates the true and exact shaping of the frame elements and the mounting of the side cheeks 1 and 2 the lateral projections 33 of which may be easily introduced into the grooves of the fixed frame elements 29 after removing one of the detachable frame elements 30.

When necessary, for instance for repairing or exchanging the pistons of the press-cylinders, both the side cheeks and the detachable frame elements may be removed after taking out the bolts 32.

I declare that what I claim is:—

1. A press including in combination a press-table forming a frame of generally rectangular shape connected with the press, a pair of side cheeks adapted to slide between and supported by two opposite sides of the frame, means mounted in the other opposite sides of the frame for adjusting said side cheeks relatively to the sides of the frame which support the side-cheeks, a plurality of transverse walls displaceably mounted between said side cheeks and means for adjusting said transverse walls relatively to said side cheeks.

2. A press including in combination a press-table forming a frame of generally rectangular shape and consisting of a pair of fixed parallel frame elements connected with the press and a pair of detachable frame elements, a pair of side cheeks adapted to slide between and supported by the fixed pair of frame elements, means mounted in

the detachable frame elements for adjusting said side cheeks relatively to the fixed frame elements, a plurality of transverse walls displaceably mounted between said side cheeks and means for adjusting said transverse walls relatively to said side cheeks.

3. A press including in combination a press-table forming a frame, consisting of a pair of fixed parallel frame elements provided with grooves at their inner surfaces, a pair of side cheeks mounted between said fixed frame elements provided with lateral projections fitting into and displaceably supported by the grooves of said fixed frame elements, provided further with grooves at their inner surfaces, a plurality of transverse walls mounted between said side cheeks having projections at both ends fitting in and displaceably supported by the grooves in said side cheeks, means for adjusting said side cheeks relatively to said frame and means for adjusting said transverse walls relatively to said side cheeks.

4. A press including in combination a press-table forming a frame consisting of a pair of fixed parallel frame elements provided with grooves at their inner surfaces and a pair of detachable frame elements, a pair of side cheeks mounted between said fixed frame elements provided with lateral projections fitting into and displaceably supported by the grooves in said fixed frame elements, provided further with grooves at their inner surfaces, a plurality of transverse walls mounted between said side cheeks having projections at both ends fitting in and displaceably supported by the grooves in said side cheeks, filling blocks inserted in the grooves of said side cheeks between said transverse walls, adapted to space apart said transverse walls, set screws arranged in said detachable frame elements bearing against side side cheeks and set screws arranged in said fixed frame elements bearing against the outer transverse walls.

5. A press including in combination a press-table forming a frame consisting of a pair of fixed parallel frame elements provided with grooves at their inner surfaces and a pair of detachable frame elements, a pair of side cheeks mounted between said fixed frame elements provided with lateral projections fitting into and displaceably supported by the grooves in said fixed frame elements, provided further with grooves at their inner surfaces, a plurality of transverse walls mounted between said side cheeks having projections at both ends fitting in and displaceably supported by the grooves in said side cheeks, transverse linings for taking wear arranged against said transverse walls provided with lateral projections fitting into the grooves of said side cheeks, linings for taking wear arranged against the

side cheeks between the transverse linings and having lateral slots fitting on the lateral projections of the transverse linings, filling blocks inserted in the grooves of said side cheeks between the transverse linings adapted to space apart said transverse linings and transverse walls, set screws arranged in said detachable frame elements bearing against said side cheeks and set screws arranged in said fixed frame elements bearing against the outer transverse walls.

10 In testimony whereof I have signed my name to this specification at Berlin, Germany.
